SLIDING SAFETY LOCK LEVER

Ernest R. Schroeder, Hawthorne, N. J., assignor
to American Car and Foundry Company, New
York, N. Y., a corporation of New Jersey

Original application September 25, 1941, Serial
No. 412,334. Divided and this application July
25, 1944, Serial No. 546,529

4 Claims. (Cl. 105—311)

This invention relates to lock levers in general and in particular to lock levers for use on drop bottom mine cars and is a division of application Serial 412,334 filed September 25, 1941.

Practically all drop bottom mine cars as now built are provided with doors hung on transversely extending hinge axes and with at least the rearmost door held in raised position by means of a latch or lock lever carried by the end wall or end sill structure of the car. In order to make these cars automatic the lever controlling the lock extends to the side of the car sufficiently to be raised by proper trackside equipment, thus releasing the lock and dropping the door. Since it is necessary for the arm to project to the side of the car, obviously this lever will strike any trackside obstructions and be easily bent or in some cases moved to an unlatched position releasing the door in the mine with consequent delay, tying up the entire mine operation. Certain cars of the automatic drop bottom type have been constructed with latching dogs engaging the lock lever to prevent its being raised, but these have not been satisfactory for they did not in any way prevent the bending of the lock trip lever. It is an object, therefore, of the present invention to provide a lever for operating the door latch, which lever has a movable end portion movable to a position within the clearance limits of the car.

A further object of the invention is the provision of a multi-part latch lever for drop bottom cars with parts of the lever slidable relative to other parts and to a position within the clearance limits of the car.

A still further object of the invention is the provision of a transversely slidable latch lever part which may be held in a retracted position within the clearance limits of the car.

These and other objects of the invention will be apparent to persons skilled in the art from a study of the following description and accompanying drawing, in which

Fig. 1 is an end view of a drop bottom mine car with the improved latch lever applied thereto;

Fig. 2 is a partial end view similar to Fig. 1 but showing the latch lever in retracted position, and

Fig. 3 is an end view of the improved latch lever.

Referring now to the drawing in detail it will be seen that the latch lever has been applied to the end wall 2 of a drop bottom mine car having a drop door 4 hinged in any suitable manner to the side sills 6. The side sills have attached thereto, as is customary, braces or gussets 8 supporting the side wings of the car and giving them

added rigidity. Any suitable type of end construction and bumper 10 is attached to the side sills to complete the frame of the car and to permit of its operation in train. The car is supported upon track rails 11 by means of wheels 12, as is customary. The car end walls are suitably braced by members 14 and carry, in the present case, a plate 16 to which is attached an offset plate 18, both plates being pierced to receive a pivot pin 20 upon which the inner part 22 of the latch lever is pivoted. The latch lever has attached thereto in any suitable manner a hook portion 24 adapted to engage under and support a tongue 26 carried by the drop bottom door. The hook is constantly urged toward door supporting position by means of a compression spring 28 interposed between the inner end of the lever and a bracket 30 fastened to the end structure of the car. In order to support the lever when the door is open, as well as to guide the lever in its vertical movements, a combined guide and support strap 32 is attached to the end wall structure of the car. The construction as described so far is more or less standard, yet subject to slight variations, such as supporting the door latch lever upon an end sill element independently of the end wall of the car.

As shown the latch lever inner part 22 is of tubular formation having a flattened part 34 by means of which the lever is pivoted on the pivot pin 20. The inner end of the tubular latch lever is closed by means of a plate 36 welded or otherwise secured thereto and adapted to coact with the spring 28 in retaining the latch hook 24 in engagement with the door projection 26. The outer end of the tubular latch lever is threaded and has secured thereto a modified cap 38, which cap is provided with a central opening 40 and a projecting hooklike finger 42. A cylindrical latch lever extension 44 of either tubular or solid construction is mounted to slide within the tubular main latch lever as is clearly shown by the drawing. This latch lever extension in the present case is of tubular form and has attached to its outer end a plug member 46 having a finger 48 formed thereon, which finger is adapted to rest within the hooklike member or finger 42 of the main part of the latch lever cap, all as clearly shown in the figures. The inner portion of the latch lever extension is provided with spaced bearing rings 50 closely fitting the inside of the tubular main latch lever part in order that the extension may not tilt within the tubular latch lever member.

With the parts in the position shown in Fig. 1

the latch lever and its extension will operate in much the same manner as the standard latch now used on the bulk of drop bottom mine cars. When, however, the car is to be sent into the mine or traverse the mine workings, the latch lever extension 44 is pushed into the main tubular part of the latch lever and the finger 48 turned so as to engage in the hook like projection 42 of the cap member 38, thus retaining the latch lever extension in the position clearly shown in Fig. 2. In this position the latch lever is located within the clearance limits of the car making it practically impossible for the lever to contact trackside obstructions and accidentally release the doors. Release of the latch lever extension is accomplished by merely rotating finger 48 out of the hook like member 42 and pulling outwardly, thus placing the extension in the position shown in Fig. 1.

From the preceding description of the latch lever and its operation it will be seen that the lever extension when in an operative position will permit the latch lever to be operated in substantially the same manner as the present standard type of latch lever. When, however, the latch lever extension is placed in an inoperative position, that is, an inoperative position so far as release of the drop bottom door is concerned, then the latch lever parts are wholly within the clearance limits of the car and trackside obstructions can not bend or distort the lever.

While the invention has been described more or less in detail with specific reference to certain modifications, it will be obvious to persons skilled in the art that various other modifications and rearrangements of parts may be made and all such modifications and rearrangements of parts are contemplated as fall within the scope of the appended claims defining my invention.

What is claimed is:

1. In a drop bottom mine car, a drop bottom door hingedly carried by the car, a latch assembly pivotally carried by the car and having a part normally engaging the door to retain the same in raised position and movable to release the door for opening, said assembly including a tubular main latch lever part located wholly within the clearance limits of the car, and a latch lever extension slidably carried within the tubu-

lar main latch lever part and slidable from a retracted position within the clearance limits of the car to an extended position projecting beyond the clearance limits of the car.

- 5 2. In a drop bottom mine car, a drop bottom door hingedly carried by the car, a latch assembly pivotally carried by the car and having a part normally engaging the door to retain the same in raised position and movable to release the door for opening, said assembly including a tubular main latch lever part located wholly within the clearance limits of the car, a latch lever extension slidably carried within the tubular main latch lever part and slidable from a retracted position within the clearance limits of the car to an extended position projecting beyond the clearance limits of the car, and means carried in part by said tubular main latch lever part for retaining said latch lever extension in retracted position.
- 10 3. In a drop bottom mine car, a drop bottom door hingedly carried by the car, a latch assembly carried by the car and normally engaging the door to retain the same in closed position and movable to release the door for opening, said assembly including a tubular main latch member located wholly within the clearance limits of the car, and a cylindrical latch member extension mounted to slide within the tubular main latch member and slidable from a retracted position within the clearance limits of the car to an extended position projecting substantially in alignment with said tubular main latch member beyond the clearance limits of the car.
- 15 4. In a drop bottom mine car, a drop bottom door hingedly carried by the car, a latch assembly pivotally carried by the car and having a part normally engaging the door to retain the same in raised position and movable to release the door for opening, said assembly including a substantially hollow main latch lever part located wholly within the clearance limits of the car, and a latch lever extension slidably carried within the hollow main latch lever part and slid-
30 able longitudinally thereof from a retracted position within the clearance limits of the car to an extended position projecting beyond the clearance limits of the car.
- 20 5. In a drop bottom mine car, a drop bottom door hingedly carried by the car, a latch assembly carried by the car and normally engaging the door to retain the same in closed position and movable to release the door for opening, said assembly including a tubular main latch member located wholly within the clearance limits of the car, and a cylindrical latch member extension mounted to slide within the tubular main latch member and slidable from a retracted position within the clearance limits of the car to an extended position projecting substantially in alignment with said tubular main latch member beyond the clearance limits of the car.
- 25 6. In a drop bottom mine car, a drop bottom door hingedly carried by the car, a latch assembly pivotally carried by the car and having a part normally engaging the door to retain the same in raised position and movable to release the door for opening, said assembly including a substantially hollow main latch lever part located wholly within the clearance limits of the car, and a latch lever extension slidably carried within the hollow main latch lever part and slid-
35 able longitudinally thereof from a retracted position within the clearance limits of the car to an extended position projecting beyond the clearance limits of the car.
- 30 7. In a drop bottom mine car, a drop bottom door hingedly carried by the car, a latch assembly pivotally carried by the car and having a part normally engaging the door to retain the same in raised position and movable to release the door for opening, said assembly including a substantially hollow main latch lever part located wholly within the clearance limits of the car, and a latch lever extension slidably carried within the hollow main latch lever part and slid-
35 able longitudinally thereof from a retracted position within the clearance limits of the car to an extended position projecting beyond the clearance limits of the car.
- 35 8. In a drop bottom mine car, a drop bottom door hingedly carried by the car, a latch assembly pivotally carried by the car and having a part normally engaging the door to retain the same in raised position and movable to release the door for opening, said assembly including a substantially hollow main latch lever part located wholly within the clearance limits of the car, and a latch lever extension slidably carried within the hollow main latch lever part and slid-
40 able longitudinally thereof from a retracted position within the clearance limits of the car to an extended position projecting beyond the clearance limits of the car.
- 40 9. In a drop bottom mine car, a drop bottom door hingedly carried by the car, a latch assembly pivotally carried by the car and having a part normally engaging the door to retain the same in raised position and movable to release the door for opening, said assembly including a substantially hollow main latch lever part located wholly within the clearance limits of the car, and a latch lever extension slidably carried within the hollow main latch lever part and slid-
45 able longitudinally thereof from a retracted position within the clearance limits of the car to an extended position projecting beyond the clearance limits of the car.
